PIPE CLEARING MACHINE

Robert G. Hunt, Los Angeles, Calif., assignor to Marco Products Company, Los Angeles, Calif., a firm

Filed May 26, 1959, Ser. No. 56,075

Term of patent 14 years

(Cl. D9—2)

Fig. 1 is a side elevational view of a pipe clearing machine of obstructions;

Fig. 2 is a rear elevational view;

Fig. 3 is a front elevational view;

Fig. 4 is a top plan view; and

Fig. 5 is a front perspective view thereof.

I claim:

The ornamental design for a pipe clearing machine, substantially as shown.
